UNITED STATES PATENT OFFICE.

HERBERT C. WIRT, OF SCHENECTADY, NEW YORK, ASSIGNOR TO GENERAL ELECTRIC CO., A CORPORATION OF NEW YORK.

LAMP-RECEPTACLE.

SPECIFICATION forming part of Letters Patent No. 729,828, dated June 2, 1903.

Application filed December 19, 1900. Serial No. 40,401. (No model.)

To all whom it may concern:

Be it known that I, HERBERT C. WIRT, a citizen of the United States, residing at Schenectady, in the county of Schenectady, State 5 of New York, have invented certain new and useful Improvements in Lamp-Receptacles, of which the following is a specification.

My invention relates to sockets or receptacles for incandescent lamps or attaching-plugs; and its object is to provide a receptacle in which the terminals are concealed and yet can be easily gotten at for making connections with line-wires.

The invention consists in a base carrying 15 the terminals and the screw-socket combined with a cover and locking-ring, as hereinafter set forth, and particularly pointed out in the claims.

In the drawings, Figure 1 is a side elevation 20 of my improved receptacle. Fig. 2 is a plan view thereof. Fig. 3 is a cross-section on line 3 3 of Fig. 2. Fig. 4 is a cross-section on line 4 4, Fig. 2.

The base A is of insulating material, such 25 as porcelain. It has a flat top and bottom, the latter being traversed by two parallel grooves a for the line-wires. At the middle of the ridge between the grooves there is preferably a slight projection a' , adjacent to 30 which are lateral grooves a^2 for the terminals. Near each end of the base are holes a^3 for the attaching-screws.

The terminals B B' are of metal, their ends 35 being slightly bent to fit across the grooves a and carrying binding-screws b to clamp the line-wires. The center terminal B has its inner end secured upon the projection a' by means of a screw b^2 . The other terminal is of horseshoe shape, partially encircling the 40 projection a' .

A socket C is attached to the base A concentric with the horseshoe-terminal. The socket is preferably of sheet metal, with a screw-thread rolled in it to fit the attaching- 45 plug or the base of a lamp. At its upper end are two inwardly-projecting flanges c , which lie between the horseshoe and the base. Screws c' , passing through the base and flange into the horseshoe, secure the socket firmly in

place. When the lamp or attaching-plug is 50 screwed into the screw-threaded socket, the terminals of said plug or lamp make contact with the terminals B B' in the usual manner.

In order to conceal the terminals B B' and make a neat finish to the receptacle, besides 55 affording a support to the socket, a cover D, of porcelain or the like, is provided, having a central hole to fit easily over the socket C. The cover may be of any desired shape; but it is preferably circular, as shown. A locking-ring E, of porcelain or the like, is screwed upon the outside of the socket to retain the cover in place. The ring may be provided with a fluted flange e to give a better hold to the fingers and to improve its appearance. 60 The ring is deep enough to conceal the socket, so that the entire receptacle appears to be made of porcelain or the like, the metal parts being entirely inclosed.

What I claim as new, and desire to secure 70 by Letters Patent of the United States, is—

1. A lamp-receptacle, comprising a base having transverse grooves, terminals lying across said grooves, a screw-threaded sheet-metal lamp-socket having flanges lying between one of said terminals and said base, a removable cover encircling the socket and extending over the grooves, and a locking-ring screwed upon the socket. 75

2. A lamp-receptacle comprising the base 80 A having on its face the side grooves a and the central projection a' , the terminals B B' connected to said base and respectively extending across said grooves, the socket C having flanges c secured to said base about the 85 central projection a' and connected to the terminal B', the cover D surrounding said socket C, and the locking-ring E having the flange e and adapted to engage said socket and hold said cover in engagement with said 90 base.

In witness whereof I have hereunto set my hand this 17th day of December, 1900.

HERBERT C. WIRT.
